United States Patent Office.

HENRY HENLEY, OF NEW GARDEN, INDIANA.

Letters Patent No. 78,738, dated June 9, 1868.

IMPROVEMENT IN PRESSES.

The Schedule referred to in these Letters Patent and making part of the same.

TO ALL WHOM IT MAY CONCERN:

Be it known that I, HENRY HENLEY, of New Garden, in the county of Wayne, and State of Indiana, have invented a new and useful Improvement in Presses; and I do hereby declare that the following is a full and exact description thereof, reference being had to the accompanying drawings, making a part of this specification.

My invention relates to an adjustable screw-beam for various kinds of presses, more particularly cider and wine-presses, whereby the screw is adjusted by lowering or swinging the screw-beam out of the way during the preparatory process, instead of adjusting the screw by turning the latter on its threads, as necessitated with ordinary presses. Thus one-half the length of screw ordinarily required may be dispensed with, and the operation of the press greatly facilitated.

To enable others skilled in the art to make and use my invention, I will proceed to describe its construction.

The uprights *d* and *d'* are hinged on bolts at *I I*.

e and *e'* are arched rods, permanently secured to the bed *a* of the press, and by means of angles at their centres, adapted to the angular surface of the uprights, serve to maintain the latter in a vertical position.

The beam *b*, in which screw *c* is held, is connected to upright, *d'*, by means of a piece, *n y*, the lower section of which is rectangular, and fitting into a rectangular mortise or recess in the top of upright, *d'*, where it is secured by a bolt or pin, on which it hinges.

The end of beam *b* that connects with the piece *n y* is provided with a suitable aperture to receive the round portion of said piece, where it is held by means of a pin. A swivel is thus formed, allowing the beam to be swung around, as seen at *x*.

The hinging of piece *n y* allows the beam to be thrown back, as shown at *u*, and by pressing the flexible rods *e* and *e'* inward, thus releasing the uprights, the latter, with the beam, may be lowered to a horizontal position, as seen at *t*.

The end of beam *b* that rests on upright, *d*, is notched to receive the end of the latter, by which they are more firmly secured together. An adjustable stirrup, *r*, secured to the upright, passes over the end of beam *b*, and secures it on said upright, in a manner allowing it to be easily adjusted.

The different methods of adjusting herein described are designed to meet the requirements of the different kinds of presses referred to.

Having thus fully described my said invention, what I claim, and desire to secure by Letters Patent, is—

1. The beam *b*, hinged at *n y*, and secured in an adjustable manner to upright, *d*, by means of stirrup *r*, (or its equivalent,) substantially as set forth, and for the purpose specified.

2. Also the flexible rods *e* and *e'*, in combination with the uprights *d* and *d'* and beam *b*, substantially as set forth, and for the purpose specified.

HENRY HENLEY.
